SPARK PLUG WITH AUXILIARY GAP

Karl Schwartzwalder, Holly, and Robert W. Smith, Flint, Mich., assignors to General Motors Corporation, Detroit, Mich., a corporation of Delaware

Original application March 17, 1945, Serial No. 583,364. Divided and this application August 25, 1949, Serial No. 115,039.

1. Claim. (Cl. 29—25.12)

This invention has to do with spark plugs having an auxiliary spark gap incorporated in the center electrode.

This application is filed under Rule 147 as a divisional application of Serial No. 583,364, filed March 17, 1945, now Patent No. 2,505,150 issued April 25, 1950.

It has long been known that the use of an auxiliary spark gap in series with gap of the spark plug will enable it to function effectively long after it would otherwise have been short-circuited by fouling, that is by the accumulation of carbon and other conducting combustion chamber products on the firing end of the plug forming a conducting path between the electrodes. This action is increased by placing the auxiliary gap as close as possible to the spark gap of the plug because the distributed capacity of the portion of the center electrode between the two gaps is thereby reduced to a minimum producing a steep wave front at the spark gap so that there is insufficient time for leakage of current through the path produced by fouling to prevent the spark from jumping the gap.

An object of the present invention is to provide an auxiliary gap of durable construction that may be readily incorporated in the center electrode of a spark plug and will operate at substantially constant voltage through the life of the plug. Another object of the invention is the provision of a simple and practical center electrode construction embodying an auxiliary spark gap.

In the drawings:

Figure 1 is a vertical sectional view through one form of spark plug embodying my invention.

Figure 2 is a vertical sectional view through a modified form of spark plug embodying my invention.

In Figure 1, 10 indicates the lower part of the metal shell of the spark plug having secured to its lower end the side electrodes indicated at 12. Within the shell is the insulator 14, preferably of aluminum oxide composition. The insulator is held in its seat in the shell by any suitable means such as by annular C-shaped spring 16, metal washer 18 and the upper part 20 of the shell which is threaded in the lower part 10 and may also be welded or brazed thereto. Suitable gaskets are interposed between the shoulders of the insulator 14 and the shell 10 and C-shaped spring 16 to distribute the pressure evenly on the insulator. The upper portion 20 of the shell is provided with the usual sleeve 22 of insulating material held in place by any suitable means. Insulator 14 is provided with a central bore 24 having an enlarged upper end and a reduced lower end. Fitted within the reduced lower end is the lower electrode section 26 which may be made of metal, such as nickel, which is resistant to heat as well as to spark erosion. This portion of the electrode has an enlarged upper end which seats on the shoulder formed at the junction of the enlarged and reduced portions of the insulator bore 24, and is preferably of hollow construction with the center filled with metal such as copper, indicated at 28, having good heat conductivity.

Above the lower electrode section is the conducting glass seal 30; above that a resistance element 32; and

2

above the resistance element a second conducting glass seal 34 on which is seated the disc 42 of the lower electrode 44 of the auxiliary gap. An additional glass seal 37 engages and grips the lower threaded or serrated end of the upper electrode element 38.

The auxiliary spark gap assembly 36 is of simple construction consisting of a sleeve 40 of insulating material, preferably steatite, although aluminum oxide or other ceramic compositions may be employed. Steatite is preferable because it may be readily cut to the desired size. The sleeve should have a rough surface to reduce the possibility of short-circuiting by deposition of the metal sputtered from the electrode. Each end of the cylinder is closed by a disc 42 having secured centrally thereto a cylindrical electrode section. The discs 42 preferably consist of heat resistant conducting material, such as commercial nickel, and the electrodes 44 are preferably made of tungsten because of its excellent resistance to heat, spark erosion and oxidation. The tungsten contacts may be secured to the nickel discs by copper brazing or the like. Other materials suitable for use as electrodes, although inferior to tungsten are platinum, platinum tungsten alloy, nickel and other alloys commonly used for spark plug electrodes. Copper will be found satisfactory where lower fabricating and operating temperatures are involved.

The auxiliary spark gap should be of such length that the voltage across it is substantially the same as that across the gap of the plug. As the pressure at the auxiliary gap is atmospheric and much lower than in the combustion chamber the auxiliary gap distance should be much greater than the spark gap.

The conducting glass seals 30 and 34 and the resistance element 32 may be of the construction described and claimed in the prior application of McDougal, Schwartzwalder and Rulka, Serial No. 488,114, filed May 24, 1943. Thus the seals 30 and 34 may be made of a fused mixture of 55 parts powdered copper, 45 parts Pyrex or borosilicate glass together with 3 parts of a suitable binder such as Dritex, a hydrogenated cotton seed oil.

The resistor 32 may be made of a mixture of 62.4% borosilicate glass (Pyrex cullet), 25.2% fluorspar (CaF₂), 7.8% magnesium borosilicate glass and 4.6% Thermax carbon, a form of carbon black.

The glass seal 37 above the spark gap may consist of Pyrex glass but the following composition is preferred:

	Per cent
SiO ₂	34
B ₂ O ₃	28
PbO	29
Al ₂ O ₃	7
Na ₂ O	2

It will be noted that this seal contains no organic binder corresponding to the Dritex used in the conducting glass seals 30 and 34. It has been found that when a binder is present in the glass seal compositions during the fusing of the glass in the insulator bore a carbon film is deposited on the insulating sleeve 40 of the spark gap, which lowers the insulation resistance of the auxiliary spark gap assembly and may cause the gap to be inoperative. However, when the binder is omitted the powdered material is difficult to handle in the small amounts required. Consequently instead of omitting a binder entirely from the composition of the conducting glass seals 30 and 34, the binder is employed to form the powdered material into pellets which are subsequently sintered, preferably in a hydrogen atmosphere, at from 1500° to 1700° F. for from fifteen minutes to one hour. The resulting pellets are substantially free from the binder and may be readily handled in manufacture.

In assembling the electrode in the insulator the lower electrode element 28 is inserted in the bore followed by the powdered or pelleted materials constituting the lower conducting glass seal 30; then by the pulverized or pelleted material forming the resistor 32 and then by the pulverized or pelleted material forming the upper conducting glass seal 34. It has been found best to use either all powdered material or all pelleted material for the parts 30-32-34 as the combination of powdered and pelleted material does not produce the desired final structure. Thereafter the spark gap assembly, the glass seal 37 and the upper electrode section 38 are inserted and the assembly is then heated to a sufficient temperature to soften the glass of the seals and resistance element whereupon the upper electrode section 38 is pressed down to cause it to seat on the upper disc 42 and make a tight assembly. On solidification the conducting glass seals 30 and 34 form an air-tight union with the walls of the bore in the insulator and grip the other parts with which they make contact.

An important feature of the invention is the character of the glass seal 37. It has been found that when a gas-tight seal is used at this location the voltage across the auxiliary spark gap increases as the plug is used because of disappearance of the air from the gap. The preferred glass composition of the seal 37 produces a crazed or finely cracked glass which, while securely united to the insulator and the cooperating parts, nevertheless permits seepage of air into the auxiliary gap. With this construction the voltage drop across the auxiliary gap has remained substantially constant throughout the life of the plug.

In the modification shown in Figure 2 the construction of the shell and the manner of mounting the insulator in the shell is substantially the same as that previously described. The electrode, however, consists of a platinum tip 50, the upper end of which is slightly enlarged and rests on a shoulder provided in the bottom of the bore 52 in the insulator. The section 54 of the electrode consists of silver cast in place. Above the silver is the glass seal 56 which may be of the copper glass composition described with the Dritex eliminated by baking the glass

pellets. If desired, a resistance may be incorporated in the glass seal as disclosed in Figure 1. 58 indicates the upper section of the electrode, the lower end of which rests on the upper disc of the auxiliary gap assembly indicated at 60. The electrode section 58 may be corrugated or grooved as in the preceding form to better interlock with the glass of the seal 57 which is of the same composition as the seal 37 of Figure 1.

Various modifications will occur to those skilled in the art. Thus, for example, compressed powdered talc could be used in place of the glass seals, suitable means being provided to hold it under compression. The upper seal instead of consisting of crazed glass permitting the entrance of air could be provided with a vent for the same purpose.

Various other modifications will occur to those skilled in the art.

We claim:

The method of making spark plugs having an auxiliary gap therein, said method comprising the steps of preparing a fired ceramic insulator with a central bore, arranging therein in the order named, a lower electrode section, a powdered mixture of glass and electrically conducting heat resistant material, an auxiliary gap assembly comprising a lower electrode, an upper electrode and a tubular insulator interposed therebetween, a quantity of powdered glass adapted after softening and cooling to form a crazed or cracked structure pervious to air and an upper electrode section, heating the assembly to soften the glass, applying pressure axially to said upper electrode section to cause it to seat in electrically circuit engaging relationship on the upper electrode of the auxiliary gap while simultaneously causing the other parts of the electrode to form a tight assembly and thereafter cooling the assembly to cause the glass to solidify in situ with the glass surrounding said upper electrode section crazing to admit air to said auxiliary gap assembly.
